UNITED STATES PATENT OFFICE.

JOHN L. BRADLEY AND RILEY T. SMITH, OF NEW HAVEN, CONNECTICUT.

JIB-HANK.

SPECIFICATION forming part of Letters Patent No. 325,047, dated August 25, 1885.

Application filed July 1, 1885. (No model.)

To all whom it may concern:

Be it known that we, JOHN L. BRADLEY and RILEY T. SMITH, citizens of the United States, residing at New Haven, in the county of New Haven and State of Connecticut, have invented certain new and useful Improvements in Jib-Hanks, of which the following is a specification, reference being had therein to the accompanying drawings, in which—

10 Figure 1 represents a perspective view of the hank, and Fig. 2 a longitudinal central section.

This invention relates to an improvement in that class of hanks which are attached to a "ship's jib," as a means of guiding the jib on its upward and downward movement on the "jib-stay," and commonly called "jib-hanks," the object being the construction of a cheap and durable article that will ride 15 freely and easily on the jib-stay without the ordinary wearing away of the material, as in the common construction, and also providing a means by which the hank can have a firm bearing upon the jib and be rigidly attached 20 thereto.

The invention consists in the construction of the hank, as hereinafter described, and recited in the claims.

A represents the hank, which is made from 30 any suitable metal, iron being preferable. From the neck or narrow portion of the hank, as at a, two ears or projections B B extend outward, perforated at their outer ends for the insertion of a pin, b, on which a roller, C, is 35 hung. The said roller C is loosely hung on the pin b, revolving freely thereon in its contact with the jib-stay, and by presenting its entire circumference for wear not only overcomes the difficulty of the wearing away of 40 the material by long usage, as in ordinary hanks, but also lessens the wear upon the

jib-stay. From the neck or narrow portion a the hank extends inward, slightly increased in width. Midway between the neck portion and the extreme inner end projections, c c, in longitudinal section, are formed to give a more perfect bearing surface for the attachment of the hank to the jib. At the inner end a triangular cut or groove is formed to grasp the jib. By the formation of the 45 projections c c a considerable bearing surface is obtained and a more perfect attachment 50 provided for.

As a convenience for attaching the hank to the jib, eyes d d are formed at the inner end 55 of the hank, by means of which attachment can be made in the well-known manner.

Having fully described our invention, what we claim as new, and desire to secure by Letters Patent, is—

1. The herein-described jib-hank, consisting of the neck portion a, forwardly-projecting ears B B, with a roller, C, hung between them, eyes d d, and the concaved face-projections c c between said eyes, substantially as 60 shown.

2. In a jib-hank having the neck portion a, ears B B, with roller C, the rearwardly-projecting eyes d d, with a concaved portion 70 between them, as set forth.

3. In a jib-hank, the combination, with the neck portion a, and means for securing the device to the jib, of the forwardly-projecting ears B B, separated at their ends and adapted to receive a roller, substantially as shown. 75

In testimony whereof we affix our signatures in presence of two witnesses.

JOHN L. BRADLEY.
RILEY T. SMITH.
